UNITED STATES PATENT OFFICE.

COLIN D. WILT, OF CHICAGO, ILLINOIS, ASSIGNOR TO CHAS. T. WILT COMPANY, OF CHICAGO, ILLINOIS, A CORPORATION OF ILLINOIS.

TRAY FASTENER FOR WARDROBE TRUNKS.

1,414,162.

Specification of Letters Patent. Patented Apr. 25, 1922.

Application filed December 24, 1921. Serial No. 524,686.

To all whom it may concern:

Be it known that I, COLIN D. WILT, a citizen of the United States, residing at Chicago, in the county of Cook and State of Illinois, have invented certain new and useful Improvements in Tray Fasteners for Wardrobe Trunks, of which the following is a specification, reference being had to the accompanying drawings, and to the reference characters marked thereon, which form a part of this specification.

This invention relates to locking attachments for wardrobe trunks. In the conventional wardrobe trunk having its sections opening on vertical hinges, it is common to provide in one section a plurality of sliding or removable drawers. In using such a trunk, it is not uncommon for the owner to leave the main sections open in his hotel room, though it is desirable to have the drawer sections locked.

The principal object of my invention, therefore, is to provide a cheap, simple and yet durable lock which may be quickly manipulated and which will hold the several drawers in proper position in the trunk section.

To the accomplishment of this object, my invention consists in the devices and combination of devices herein shown and described, and particularly set forth in the appended claims.

In the drawing:

Fig. 1 is a perspective view of a conventional wardrobe trunk with its two sections open to show my invention applied thereto.

Fig. 2 is a vertical sectional view of the drawer section.

Fig. 3 is a perspective view, enlarged, of a portion of the trunk.

Fig. 4 is a perspective view of one of the engaging plates.

Fig. 5 is a perspective view of the stirrup plate.

Fig. 6 is a perspective view of the locking bar, being broken away to show both ends.

Referring to the drawings, A represents the trunk as a whole, having a drawer section B and a clothes-hanging section C. As the construction of these sections forms no particular part of my invention, further detailed description is omitted.

The section B is provided with a plu-

rality of horizontal, removable, sliding drawers 1, and in the upper end with a hat compartment 2, closed by a lid 3 hinged at its lower margins at 4, 4. The gable portion of the trunk is provided with a front wall 5 to carry the hasp 6 of a suitable lock covered by the escutcheon plate 7, the lock and the escutcheon plate of course being in the hinged cover 3. D is a stirrup plate which may be secured by rivets 8 or otherwise to the lower one of the removable drawers 1. It preferably is provided with a rearwardly extending flange d and also with a stirrup strap 9. The strap 9 may be separate as shown in Fig. 5, or it may be an integral part of the plate D. Secured to the under part of one of the drawers 1, or to some other fixed support, such as the bottom of the hat compartment 2, by screws or rivets, passing through apertures e are the plates E. Each plate E is provided with an elongated recess 10 extending inwardly from one of its side margins, and the plate is so positioned that the recessed portion projects outwardly and beyond the front margin of the drawers 1, with the recess vertically above the recess formed by the stirrup 9.

F is a locking bar of suitable metal, preferably of reduced width at its lower end 11, to form shoulders 12, 12. The lower end is designed to fit nicely into the strap 9 of the plate D, and the shoulders 12 to rest upon the upper margins of the stirrup strap 9. The thickness of the bar F is such as to correspond with and nicely fit within the recesses 10 of the plates E. The upper portion of the lock bar F is preferably provided with an elongated slot 13 so shaped and arranged as to straddle and expose the key-hole 14 and the latch knob 15 on the escutcheon plate 7. The upper member 16 of the bar F will preferably be of such shape as to fit within and under the bent portion 17 of the hasp 18, which is hingedly connected at 19 to the front wall 5.

In locking the various drawers and compartments, the user will first close the lid 3 and lock it in position through the key-hole 14 in the familiar manner. The user will then take the bar F and place it in juxtaposition to the plates D, E, and first insert the lower end 11 in the stirrup plate D and then by a side-wise or lateral movement, slip the bar F into the recesses 10 of

the several plates E, in which position the upper end of the bar F will rest upon the escutcheon plate 7 with the slot 13 exposing the key-hole 14, the knob 15 and the aperture 20, into which the catch 21 of the hasp 18 will engage. The hasp 18 may then be brought down so that the part 17 will cover the cross bar 16 of the bar F and the latch 21 inserted in its appropriate aperture 10 through the escutcheon plate.

The lock used will be one of any general and conventional type, whereby the key inserted through the key-hole 14 will lock both the hasp 18 and the knob 15 against movement.

It will thus be seen that the lid 3 and the several drawers 1 will all be securely positioned and locked, and the trunk may be left open with impunity. Of course, to remove 20 the contents of any of the drawers, it will first be necessary to unlock the device, move the knob 15, release and raise the hasp 18 and then by slightly raising the bar F as a whole and moving it sidewise until it is disengaged from the notches 10 of the plates E, access may be had to the several compartments.

It is obvious that slight modifications may be made in the details of construction. For 30 example, the stirrup plate D is shown in Figs. 1 and 2 as located near the top of the lower drawer 1, whereas of course it may be located near the bottom or be secured to the bottom wall 22 of the trunk section A. Likewise, the plates E may or may not be used, as desired, or any number may be used. Similarly, the shape of the upper end 35 of the lock bar F may be varied to suit the kind of lock employed or the design and configuration of the hasp 18. I therefore do not desire my invention limited to the precise construction illustrated and described, except as may be pointed out in the 40 claims.

45 I claim as my invention:

1. A tray fastener for wardrobe trunks comprising in combination with a trunk section provided with a plurality of movable trays, a lock hasp hingedly secured to a fixed support, a stirrup support, a metal bar removably positioned over the front of the trays and extending from the stirrup to the hasp and operative connections between said bar, the hasp and the stirrup.

50 2. A tray fastener for wardrobe trunks comprising in combination with a trunk section provided with a plurality of movable trays, a lock hasp hingedly secured to a fixed support above the uppermost tray compartment, a stirrup support at the lower end of the trunk, a metal bar removably positioned

over the front of the trays and extending from the stirrup to the hasp and operative connections between said bar, the hasp and the stirrup.

65

3. A tray fastener for wardrobe trunks comprising in combination with a trunk section provided with a plurality of movable trays, a lock hasp hingedly secured to a fixed support above the uppermost tray compartment, a stirrup support at the lower end of the trunk, a metal bar removably positioned over the front of the trays and extending from the stirrup to the hasp, operative connections between said bar, the hasp and the stirrup, and a slotted plate engaging the bar intermediate the hasp and the stirrup.

70

4. In a trunk section provided with a plurality of movable trays, the combination of a stirrup support, a hinged hasp and a lock member, of a metal bar having its upper and lower ends complementally formed to engage the hasp and the stirrup, respectively, and being suitably apertured at its upper portion to straddle the lock member.

75

5. A wardrobe trunk having a plurality of slidable trays and a compartment closed by a hinged lid, a lock member on the lid, a hinged hasp on a fixed support to engage the lock when the lid is closed, a stirrup support, a flat metal removable bar stepped in the stirrup support and extending upwardly in front of the trays and the hinged lid and held at its upper end by the hasp and slotted plate projecting beyond the face of the trays and engaging said bar intermediate its ends.

80

6. A tray fastener for wardrobe trunks comprising in combination with a trunk section provided with a plurality of movable trays, a lock hasp hingedly secured to a fixed support above the uppermost tray compartment, a stirrup support at the lower end of the trunk, a metal bar removably positioned over the front of the trays and extending from the stirrup to the hasp, operative connections between said bar, the hasp and the stirrup, said operative connections embracing a shoulder to the bar at its lower end, an elongated slot in the upper end of the bar, and a transversely extending recess in the hasp for engagement with the upper end of the bar.

85

7. In testimony that I claim the foregoing as my invention I affix my signature, in the presence of two witnesses, this 21st day of December, 1921.

COLIN D. WILT.
